Filed June 6, 1974, Ser. No. 476,768

Term of patent 14 years

Int. Cl. D16—06

U.S. Cl. D57—1 E

Fig. 2

Fig. 3

FIG. 1 is a right side elevation of an ocular assembly for a riflescope, showing my new design;

FIG. 2 is a top plan view thereof taken in the direction of line 2—2 on FIG. 1; and

FIG. 3 is an end elevation thereof taken in the direction of line 3—3 on FIG. 1.

The unillustrated left side surface is a mirror image of the right side surface shown in FIG. 1. The unillustrated bottom surface is substantially identical to the top surface shown in FIG. 2. The riflescope barrel shown in broken lines in FIG. 1 is for illustrative purposes only.

I claim:

The ornamental design for an ocular assembly for a riflescope, substantially as shown and described.
